United States Patent Office

Des. 186,131
Patented Sept. 15, 1959

186,131

SPANNER WRENCH

Arlie A. Wallace, Long Beach, Calif.

Application January 15, 1958, Serial No. 49,266

Term of patent 3½ years

(Cl. D54—16)

Figure 1 is a perspective view of a spanner wrench embodying my new design;

Figure 2 is a perspective view of the spanner wrench viewed from the opposite side thereof;

Figure 3 is a cross sectional view through the handle portion of the wrench; and

Figure 4 is a cross sectional view through an end portion of the wrench taken on the plane of the line 4-4.

I claim:

The ornamental design for a spanner wrench, as shown.
